BLOWER UNIT FOR WALL HEATERS

Harry E. Thompson, Steubenville, Ohio, assignor to The Ohio Foundry & Manufacturing Company, Steubenville, Ohio, a corporation of Ohio

Application November 10, 1955, Serial No. 546,207

1 Claim. (Cl. 98—38)

This invention relates to an improvement in wall heater units of the type usually heated by the combustion of manufactured or natural gases and located between the studding of a partition or wall or on the wall of a room.

Under present conditions the heat flows out through downwardly directed louvers in the front of the standard panel and gravitates toward the ceiling of the room space, and of course to some extent radiates by convection from the panel itself.

One of the objects of the present invention is to provide a forced air unit to be mounted above the upper end of the standard front panel of a wall heater for the purpose of causing the air issuing from the standard front panel to be directed outwardly by suction and velocity pressure to maintain better diffusion, to heat the lower portion of the room space and floor area, before the tendency of hot air to rise from the standard panel, takes effect. That is to say, the present invention contemplates the provision of a self-contained unit including blower means which may be conveniently attached or fitted to the upper end of a louvered heater panel to force the heated air coming out of the wall heater proper downwardly along the floor area and across the room, as well as in directions to the right or left of the unit, thus heating the entire room from the floor upwardly before the normal tendency of hot air to ascend in the usual fashion. In this way the heater not only becomes more efficient but provides a more even room temperature from the floor level to the breathing level, which is a feature most desired from any type of heating system, and is difficult to achieve with straight gravity heating.

Another object of the invention is to provide a novel unit including structural features in the form of a blower housing, having openings through which the room air and warmer ceiling height air is drawn into the blowers and forced downwardly through louvers at the front side of the blower unit to intercept and entrain heated air tending to rise from the front of the panel.

A further object of the invention is to provide simple and practical means for mounting the unit above the panel.

A still further object is to provide a blower unit whose motors may be controlled by a manual switch, or by a thermal heat responsive type of switch, as required by the user.

With the above and other objects in view which will more readily appear as the nature of the invention is better understood, the same consists in the novel combination and arrangement of parts shown in the accompanying drawing, in which:

Fig. 1 is a perspective view showing the forced air unit mounted on the upper portion of a wall heater panel.

Fig. 2 is a vertical cross section of the unit shown in Fig. 1.

Fig. 3 is a rear elevation of the forced air unit shown in Fig. 1.

Similar reference characters designate corresponding parts throughout the several figures of the drawing.

Referring first to Fig. 1, it will be seen that the forced air unit as a whole is designated generally as A and is intended to be mounted above and at the upper end of the main wall panel B, the latter having the usual side and front walls, the front wall including the downwardly directed front louvers B'.

Reverting to the forced air unit A, the same comprises 10 a housing having a front wall 1, downwardly directed louvers 2, opposite side walls 3—3, a top wall 4, and, as will be seen from Fig. 2, the unit is open at the rear where it communicates with the wall space in the rear of the heater.

15 The casing of the blower unit is depressed outwardly as shown at 5 in Figs. 1 and 2 to better accommodate the blowers, later to be described. The side walls 3 have air intake openings 3^a and the top wall has air intake openings 4^a which may be of any geometrical design, such for example as shown by the elongated slots.

20 It will also be seen from Figs. 2 and 3 that the top wall 4 is provided with an inturned flange 4^b, and that the side walls are provided with inturned flanges 3^b, the latter fitting flushly against the wall surface. In order to mount 25 the unit above the panel B, it is preferred to mount the same on a hanger plate P which, as will be seen from Fig. 2, is in the form of an angle member whose inner and downwardly directed leg is intended to be secured to the wall surface while the outer upturned end and the horizontal 30 connecting web form a seat for receiving the down-turned flange 4^b of the casing. The outer flange of the hanger will prevent the unit from rocking forwardly away from the wall, and the entire hanger enables the weight of the blower unit to be supported substantially independently of the front panel B but in alignment therewith, as will be seen from Fig. 2.

Concealed behind the front wall 1 and the side walls 3 there is provided a duct member C of angular cross section which extends horizontally within the blower 40 casing but preferably terminates slightly short of the inner sides of the walls 3—3. The duct C includes a deflector wall 6 which inclines forwardly, that is, from the rear towards the front of the unit, and a horizontal web 7, which receives through suitable openings therein, the 45 outlet ends 8 of the blowers proper designated generally as D. Thus it will be seen that room space air taken in through openings 3^a and 4^a will be recirculated by the blowers D through the duct formed by 6, 7 and the inner faces of the side walls 3 to the outlets 8 and against the deflector wall 6 so as to forcibly direct heated air 50 outwardly and downwardly through the louvers 2 to cross the path of heat issuing through louvers B' of main panel B.

55 Referring more particularly to Fig. 3, it will be seen that it is preferred to employ a blower, or as shown, a pair of blowers D operated by the same motor E from a common shaft. The casings of the blower units D will fit into the cavity formed by the outwardly deflected portion 5 of the front wall, while as previously indicated the outlets 8 are directed downwardly toward the deflector wall 6. For the purpose of firmly anchoring the motor and blower units in place, there is provided a two-part 60 clamp 9—10. The front portion of this clamp is medially bowed to fit the motor casing and opposite ends thereof are preferably welded as at 9^a to the inside face of the front wall above and below the outwardly depressed portion 5. The other portion 10 of the clamp is also medially bowed to fit the housing of the motor E while its free end 65 portions are flattened and receive the screws 11 which are threaded into tapped holes in the part 9 of the clamp. The blower housings are secured to the housing of the

motor E with the aid of non-metallic gaskets 12, and the inner sides of the clamp elements 9 and 10 where they engage with the housing of the motor E, may also be lined with non-metallic sound deadening material in order that the quiet operation of the blower unit may be insured.

The motor E is suitably connected with available house current by the leads 13 and 13^a which lead into inlet box 14. This box is secured to the rear side of the deflector wall 6. The circuit arrangement is such that current to the motor E may be controlled by a manual switch S on one of the outer side walls of the casing or by leads 15 connected with a thermally operated switch designated generally as T. Thus, it will be seen that the blower units may be operated automatically or manually, as desired.

From the foregoing it will be seen that the present invention fulfills the object previously stated, namely to provide a forced air unit at the top of a wall heater to insure heated air to be directed to where it will be more efficient and to provide more comfortable living area in room space to be heated.

I claim:

A wall heater comprising a main front panel having a louvered front wall and rearwardly directed side walls, the space between the upper edges of the front wall and the side walls being open to permit the escape of heated air currents, a blower housing surmounting the panel and having a louvered front wall and side and top walls each having air intake openings, the bottom edges of said

front and side walls being formed for registry with the corresponding upper edges of the main panel so that the blower housing receives said heated air currents, a forced-air-duct-forming and blower-means-supporting member 5 of angular cross section disposed horizontally across the space between the side walls of the blower housing and in the path of said heated air currents, said member including a horizontal shelf portion located at the rear of the louvered front wall of the blower casing and a portion inclined forwardly and downwardly to direct forced air currents toward the louvered front wall of the blower housing, blower means supported on said horizontal shelf portion and including a motor and a casing having its discharge outlet directed toward the outer face of the 10 inclined portion of said member, said blower means when in operation drawing air through the openings of the side and top walls of the blower housing and discharging it onto the outer face of the inclined portion of the duct forming member to conduct a forced air blast through 15 the louvered front of the blower housing and across the path of heat currents rising from the louvered front wall of the main panel.
